UNITED STATES PATENT OFFICE

163,972

NECKTIE

Alfred P. Slaner, Scarsdale, N. Y.

Application March 8, 1951, Serial No. 14,422

Term of patent 3½ years

(Cl. D3—16)

To all whom it may concern:

Be it known that I, Alfred P. Slaner, a citizen of United States, residing at Scarsdale, in the county of Westchester and State of New York, have invented a new, original, and ornamental Design for a Necktie, of which the following is a specification, reference being had to the accompanying drawing, forming part thereof.

The figure on the drawing is a front perspective of a necktie, showing my new design.

The said necktie is of the conventional type and the dominant feature of the design is the surface ornamentation on the large tab as shown.

I claim:

The ornamental design for a necktie, substantially as shown and described.

ALFRED P. SLANER.
